J. J. O'Leary
ATTORNEY.

UNITED STATES PATENT OFFICE.

WALTER R. EHA, OF DENVER, COLORADO.

LAMP SHADE.

Application filed July 20, 1926. Serial No. 123,680.

My invention relates to shades for electric lamps and its principal object is to provide a movable shade of novel construction which may be adjusted to obscure, modify or deflect the light rays emanating from the lamp of an electric light fixture in various relative positions.

Another object is to provide a shade of the above described character, which is of highly artistic and ornamental appearance, and further objects reside in details of construction as will appear in the course of the following description.

An embodiment of the invention has been illustrated in the accompanying drawings in the several views of which like parts are similarly designated and in which

Figure 1 represents a face view of a wall or bracket fixture equipped with a shade of the improved construction;

Figure 2, a side elevation of the fixture shown in Figure 1, drawn to an enlarged scale, with the shade in a partially closed position;

Figure 3, a vertical section along the line 3—3 Figure 1, drawn to an enlarged scale, with the shade in a partially open position;

Figure 4, an enlarged section taken on the line 4—4 Figure 1;

Figure 5, an elevation of a standing or pedestal lamp to which the improvements are applied;

Figure 6, an elevation of the upper portion of the lamp of the type shown in Figure 5, illustrating a modification in the construction of the shade associated with the same.

Figure 7, a side elevation of the upper portion of the lamp shown in Figure 5, looking in the direction of the arrow A, with the shade in a different adjusted position, and

Figure 8, a side elevation of a wall lamp of the type illustrated in Figure 1, showing a shade of modified construction.

Referring further to the drawings, the fixture illustrated in Figures 1 to 4 comprises a base plate 5 adapted to be suspended from a wall or otherwise supported, and provided with a socket 6 for the connection of an incandescent lamp 7 in an electric lighting circuit. The plate has in concentric relation to the socket, a circular ridge 8 upon which is fastened an annular trough 9 of channel section.

At diametrically opposite points of the ridge are forwardly projecting lugs 10 for

the support of the lamp shade 12. The shade is composed of a plurality of bent frames 13 preferably of semi-circular form, provided with eyes 14 to connect their extremities to the lugs.

The connections are made through the medium of headed stud-bolts 15 which are screwed into threaded central apertures of the lugs 10. The shanks 16 of the studs support the ring-shaped extremities of the frames, and washers 17 of elastic material, placed between the extremities of the frame and the lugs, serve to yieldingly resist the rotary adjustment of the same. The eyes of the frames are offset at different distances so that the frames may be made in pairs of identical shape for economy in manufacture and so that when the frames are assembled they may be positioned to cover one another as has been best shown in Figure 4 of the drawings.

The frames are connected by a covering 18 of flexible material preferably made in sections and secured by sewing or any suitable method. The joints between the sections of the covering, over the frames may be covered by strips 19 of braid of ornamental design.

The frames are preferably made of heavy wire with the exception of the end frames 13^a which may be made of metal of angle-section to facilitate fastening of the edges of the covering thereto. When the end frames 13^a are placed in their extreme positions in which they are disposed within the annular trough at opposite sides of the lamp, the other frames are spaced equidistantly apart and the covering forms a shade of hemispheric form that completely encloses the electric light bulb.

The washers 17 are placed between the eyes of the outer frames 13^a and they are held against rotation by pins 10^a on the lugs 10 so that when the frames 13 are adjusted, the frames 13^a will remain in place.

The covering is preferably made of translucent material and by making the various sections thereof in different colors, artistic effects may be produced, and when the shade is adjusted to but partially screen the light, its color can be varied according to the taste or requirements of the occupants of a room in which the fixture is installed.

Figure 1 shows the shade in its hemispheric form in which it completely encloses the lamp; in Figure 2 the shade is adjusted to form a canopy which screens the light

above the lamp, and in Figure 3 the shade has been illustrated in a further closed position so as to obscure the greater part of the light rays emanated from the electric lamp.

In Figure 8 of the drawings the shade has been shown as made in two separate parts 20 by omitting one of the sections of the covering between two of the frames, this form 10 of the invention being desirable under certain conditions, inasmuch as it permits of shading two or more different portions of the lamp at one time and facilitates adjustment to a completely open or completely 15 closed position.

Figures 5, 6 and 7 show the shade applied to a pedestal lamp. The frames and the covering constituting the shade are in this form of the invention arranged to form a 20 spherical shade which completely encloses one or more lamps.

The frames are mounted at opposite ends of a semi-circular fork 21 on a standard 22 by means similar to those hereinbefore described with reference to the form of the invention shown in Figures 1 to 4 and the lamp sockets may for convenience be mounted on a post 23 extending from the upper end of the standard.

30 The shade is preferably made in two hemispherical parts 24 which may be separately adjusted as shown in Figure 5 or it may be made in a larger number of parts 25 also separately adjustable as illustrated in Figure 6.

Having thus described my invention it will be apparent that the shade may be adjusted to many different positions and if made of sections of different shades or 40 colors, to produce several different light effects. This is of advantage not only from a decorative or ornamental point of view but also because it permits of modifying the effect of the light upon the eyes of the occupants of a room in which the fixture is 45 installed.

The studs on which the frames of the shade are mounted, and the resilient washers cooperate to frictionally hold the frames in 50 their adjusted positions, so that they may be moved in either direction and so that they will remain in place without adjustment of the studs.

The flexible fabric or other material of 55 which the covering is composed, folds between the frames so that the latter may be placed close together when the shade is completely or partially opened, and it will be understood without further illustration that 60 the shade of the forms shown in Figures 5, 6 and 7 may be applied to a hanging lamp as well as to a lamp of the pedestal type.

It will be further understood that while 65 my invention is particularly adapted for use in connection with electric light fixtures in-

stalled in residences and other buildings, it may also be utilized on lamps of automobiles and other vehicles and that while the bent frames have been shown in semi-circular shape they may be differently formed. 70 Changes in the construction and the arrangement of the parts other than the modifications illustrated in the drawings and herein described, may be resorted to without departing from the scope of the invention as 75 defined in the hereunto appended claims.

Having thus described my invention what I claim and desire to secure by Letters Patent is:

1. In an electric light fixture, a support 80 having a lamp-socket and a channel around the same, and a shade composed of bent frames mounted at their ends at opposite sides of the channel to turn about a common axis, and a flexible covering fastened to the frames, the channel being adapted to admit an end-frame of the shade.

2. In an electric light fixture, a support 90 having apertured lugs, headed studs on the lugs, and a shade composed of bent frames having eyes around the studs for their rotary support, and a flexible covering fastened to the frames, the studs frictionally holding the frames in independently adjusted positions.

3. In an electric light fixture, a support, members on the support having threaded apertures, headed studs having threaded extensions in the apertures, a shade composed of bent frames having eyes around the studs, and a covering for the frames, the eyes being frictionally held in independently adjusted positions by compression between the members and the heads on the studs. 100

4. In an electric light fixture, a shade composed of bent frames, each frame being independently movable to a variety of positions, a flexible covering on the frames and means to maintain each frame in each of its positions. 110

5. In an electric light fixture, a shade composed of bent frames, each frame being independently movable to a variety of positions, a flexible covering on the frames and frictional means to maintain each frame in each of its positions. 115

6. In an electric light fixture, a support having a lamp socket and a lip around the same, a shade composed of bent frames mounted to turn independently about a common axis and a covering fastened to the frames, the shade together with the support being adapted to enclose the socket, and the lip being adapted to lap the end frames of the shade when in said enclosing position, whereby to prevent the escape of light between the frame and the support. 120

In testimony whereof I have affixed my signature.

WALTER R. EHA.
